(No Model.)

B. MARTIN.

HYDROCARBON BURNER.

No. 293,972.

Patented Feb. 19, 1884.

UNITED STATES PATENT OFFICE.

BRUNO MARTIN, OF EAST SAGINAW, MICHIGAN.

HYDROCARBON-BURNER.

SPECIFICATION forming part of Letters Patent No. 293,972, dated February 19, 1884.

Application filed August 27, 1883. (No model.)

To all whom it may concern:

Be it known that I, BRUNO MARTIN, of East Saginaw, in the county of Saginaw and State of Michigan, have invented new and useful 5 Improvements in Hydrocarbon-Burners; and I do hereby declare that the following is a full, clear, and exact description thereof, reference being had to the accompanying drawings, which form a part of this specification.

10 This invention relates to certain new and useful improvements in the construction of hydrocarbon-burners, by means of which a great spread is given to the flame and a more perfect combustion obtained than can be had 15 in the use of devices for this purpose as ordinarily constructed. This improved burner will be found very beneficial in the consumption of hydrocarbons in a vaporized form, where an intense heat is desired—as, for instance, in stoves either for heating or cooking 20 purposes, under boilers, and in many other places—with great economy in the amount of the hydrocarbon used.

The invention consists in the peculiar construction of the various parts and their combination and operation, as more fully hereinafter described.

Figure 1 is a central vertical section of my improved burner. Fig. 2 is a horizontal section on the line X X in Fig. 1.

In the accompanying drawings, which form a part of this specification, A represents a shell, open at bottom, and provided with an inwardly-deflecting flange, a, at its top end. 35 B is an inner shell, shorter than the shell A, also open at bottom, and also provided at top with an inwardly-deflecting flange, b. These two shells are arranged with relation to each other, as shown, having a free air-space between them.

C is an interior shell, in the form of a truncated cone, the lower end flaring outwardly, as shown, open at top and bottom, and at top also provided with an inwardly-deflecting 45 flange, c, and arranged to form a clear air-space between it and the shell B.

D is a heavy metallic cup, preferably made of brass, with a concave bottom, as shown, between which and the vertical sides of the 50 cup the sides are also concave. This cup is internally threaded, and is provided with a

flanged and threaded plug, E, which screws into and forms a cover for the cup.

F is a pipe cast with or attached to one side of the cup, projecting through the shells A B 55 C, through coincident holes for the purpose, and the projecting end of this pipe is closed by a plug, G.

H is a feed-pipe passing through coincident holes in the three shells opposite the pipe F, and is screwed into the side of the cup, as shown, in axial line with the pipe F. A connection between the two pipes and through the cup is formed by means of a perforated pipe, I.

J is a branch pipe leading from the pipe F down between the shells A and B to the burner K, which is provided with a pin-plug, screwed into the burner, of the usual construction, and the burner is also provided with a 70 cup, L, to receive alcohol or its equivalent, setting fire to which vaporizes the hydrocarbon in the burner and ignites it.

M is a metallic ring-plate laid upon the top of the cup before the plug E is screwed on. 75 This ring projects beyond the top of the cup, to form a deflecting-flange between the deflecting-flanges b c.

N is another similar ring, laid upon the ring M, and its edge is turned upwardly and outward to meet the flat metallic plate O. After the two rings are in position, the plug E is screwed to place, and holds said rings in position. The plate O is then laid upon the top of the plug E, said plate projecting beyond the upwardly-projecting edge of the ring N. Another plate, P, with its periphery bent upwardly and outwardly, is placed to meet the plate Q, which projects beyond the flanges of the plate P, just below the plane of the deflecting-flanges a. The plates O P Q are secured to the top of the plug E by means of the screw R, a hole being tapped into the top of the plug for that purpose. The cup is filled with any suitable granulated refractory material, which serves to check the too rapid flow of the hydrocarbon through the cup, and the pipe H, being connected with any suitable source of supply filled with hydrocarbon, the latter is discharged into the cup through the 90 perforated pipe I, when it is absorbed by the refractory material which fills the intervening

100

space, thus exposing the hydrocarbon to a large area of heated surface, which is thereby quickly and thoroughly vaporized by the heat from the burner, the vapor or gas finding an outlet through the pipe J to the burner. The flame is inclosed within the shell C, which directs such flame against the bottom of the cup, the concavities in the bottom of which tend to spread the flame around the cup and to the annular passage formed by the deflecting-flanges c, and thence through the tortuous passage formed by the rings M N, plates O P Q, and deflecting-flanges ab, the spaces between the shells furnishing the necessary amount of oxygen to produce the most perfect combustion, so that no smoke or smell arises as the result of imperfect combustion.

In the construction described, the shells are supported by the pipes F H. To provide against any accidental displacement, a stay, S, is run through coincident holes in such shells, the end of such stay being screwed into a hole tapped in the wall of the cup for that purpose, as shown in Fig. 2.

I deem it important that the chamber D be arranged centrally over the burner, for by this means the hydrocarbon, in its passage through the refractory material, is vaporized much more readily and evenly than it is where the burner is placed under one end of the vaporizing-chamber, as has heretofore been proposed.

What I claim as my invention is—

1. In a hydrocarbon-vapor burner, horizontal deflectors overlapping each other in vertical series, in combination with shells and cup, substantially as and for the purposes described.

2. The combination, with a burner, of a cup provided with supply and exit pipes, a perforated pipe passing through said cup, connecting such supply and exit pipes, and refractory material around said perforated pipe, substantially as set forth.

3. In a hydrocarbon-burner, horizontal deflectors in vertical series, with inclined deflectors interposed between them, in combination with a vaporizing-cup, substantially as and for the purposes described.

4. In a hydrocarbon-burner, a vaporizing-cup provided with suitable inlet and outlet

pipes and a plug secured therein, performing the double function of forming a cover for the cup and holding the plates M and N between the projecting flange of said plug and top of the cup, substantially as specified.

55

5. In a hydrocarbon-burner, the combination of a vertical series of horizontal deflectors with vertical annular ducts, forming air-passages to the flame in its passage around said deflectors, substantially as described.

60

6. In a hydrocarbon-burner, a vaporizing-cup formed with a concave bottom and sides, in combination with an inclosing-shell, substantially as and for the purposes specified.

7. In a hydrocarbon-burner, and as a means for producing an undulating or tortuous flame, the combination of the horizontal deflectors, in vertical series, with the deflecting-flanges of the inclosing-shells, forming the air-ducts, substantially as set forth.

70

8. The combination, with a vaporizing-cup and hydrocarbon-burner, of the inner conical shell or ring-duct provided with a deflecting-flange, for the purpose of guiding and deflecting the flame against the bottom and side walls of such cup, substantially as described.

9. In a hydrocarbon-burner, a vaporizing-chamber filled with granulated refractory material, such chamber being arranged centrally over the burner, and communicating therewith by a pipe, and adapted to receive the hydrocarbon from any suitable source, substantially as specified.

10. In a hydrocarbon-burner, a series of annular air-ducts of graduated size, concentrically surrounding the burner, and each provided at top with an inwardly-projecting deflecting-flange, for the purpose of supplying oxygen at succeeding intervals to a flame, substantially as set forth.

90

11. A hydrocarbon-burner consisting of the shells A B C, with their flanges ab c, vaporizing-cup D, plug E, pipes F H I J, burner K, rings M N, and plates O P Q, the parts being constructed, arranged, and operating substantially as and for the purposes described.

BRUNO MARTIN.
